VARIABLE SPEED MOTOR DRIVE

Paul B. Reeves and Harry E. Brooks, Columbus,
Ind., assignors to Reeves Pulley Company, Co-
lumbus, Ind., a corporation of Indiana

Application March 16, 1936, Serial No. 69,113

6 Claims. (Cl. 74—230.17)

The present application relates to a variable speed motor drive, which might also be described as a unitary drive and transmission consisting of a motor and a countershaft, with expansible pulleys carried upon the motor spindle and the countershaft, and means for controlling the effective diameters of the respective pulleys to vary the speed ratio between the motor spindle and the countershaft, the whole organization being carried on a unitary base with which, if desired, there may be associated an enclosing cover or housing.

A primary object of the invention is to provide simplified structure of the character described, which shall nevertheless be highly efficient and accurate in operation, and control. Further objects of the invention will appear as the description proceeds.

To the accomplishment of the above and related objects, our invention may be embodied in the form illustrated in the accompanying drawing, attention being called to the fact, however, that the drawing is illustrative only, and that change may be made in the specific construction illustrated and described, so long as the scope of the appended claims is not violated.

The figure is a plan view of one embodiment of our invention.

Referring more particularly to the drawing, it will be seen that we have illustrated a base 10 upon which is mounted a shaft 11, said shaft being journalled in bearings 12 and 13 provided by posts upstanding from said base. A coned disc 14 having an elongated hub 15 projecting from its coned face, is fixed to the shaft 11 through the medium of any suitable fastening means, as 16. A similar coned disc 17 is splined on the hub 15 in facing relation to the disc 14; and a coiled spring 18 is sleeved on the hub 17 of the disc 17 and bears against the disc 17 and a stop collar 19, carried at the end of the hub 15, said spring 18 constantly urging the disc 17 toward the disc 14.

The base 10 is formed to provide a slide way 20 upon which is slidably carried a motor bed plate 21 carrying a motor 22 which has the usual spindle 23. A coned disc 24 having an elongated hub 25 projecting from its coned face is fixed to the spindle 23 through the medium of suitable fastening means, as 26. Said disc 24 and said disc 14 face in the same direction.

A similar coned disc 27 is splined on the hub 25 in facing relation to the disc 24, and a thrust bearing 28 is so connected to the hub 27 of the disc 27 as to prevent relative axial movement

between said disc 27 and said bearing 28. Said bearing 28 is provided with oppositely projecting trunnions 29, 29 which are embraced by the arms of a bracket 30 rigidly secured to, and projecting upwardly from, the base 10. Obviously, this arrangement prevents movement of the disc 27 in the direction of its own axis.

A screw shaft 32 is journalled in a bearing 33 carried by the base 10, and is operatively associated with the motor bed plate 21, said shaft 32 being provided with a hand wheel 34 positioned outside the bearing 33.

An edge-active belt 35 provides a driving connection between the cone pair 24, 27 and the cone pair 14, 17.

The operation of the illustrated organization will be entirely clear. Assuming that the motor 22 is energized, the shaft 11 will be driven, when the parts are in their illustrated positions, at an angular velocity considerably greater than the angular velocity of the spindle 23. If, now, the hand wheel 34 is rotated in a counter-clockwise direction, as viewed from the left of Fig. 1, the motor 22 will be shifted toward the left, carrying with it its spindle 23 and the disc 24 which is fixed thereon. The bracket 30 will prevent corresponding axial movement of the disc 27, so that the discs 24 and 27 will be separated. The spring 18 will thus be permitted to force the disc 17 toward the disc 14, squeezing the belt 35 outwardly between said discs, and pulling the belt more deeply into the crotch between the discs 24 and 27, whereby the angular velocity of the shaft 11 will be reduced.

Correspondingly, clockwise rotation of the hand wheel 34 will shift the disc 24 toward the disc 27, squeezing the belt 35 outwardly between said discs, and pulling it more deeply into the crotch between the discs 14 and 17 to force the disc 17 toward the right against the tendency of the spring 18, whereby the angular velocity of the shaft 11 will be increased.

We claim as our invention:

1. In a device of the class described, a base, a shaft associated with said base, a coned disc fixed on said shaft, a second coned disc slidably mounted on said shaft in facing relation to said first disc, spring means urging said second disc toward said first disc, a motor carried by said base and having a spindle, a third coned disc mounted on said spindle and oppositely faced with respect to said first disc, means securing said third disc against movement in the direction of its own axis, a fourth coned disc mounted on said spindle between said third disc and said motor, a belt

- providing a driving connection between said disc pairs, and means for positively shifting said motor and spindle axially in either direction, said fourth disc being fixed on said spindle.
5. 2. In a device of the class described, a shaft, a second shaft substantially parallel with said first-mentioned shaft, an expansible V-pulley mounted on one of said shafts, an expansible V-pulley mounted on the other of said shafts, an edge-active belt providing a driving connection between said pulleys, means for shifting one only of said shafts axially to effect an adjustment in the effective diameter of the pulley, carried by said one shaft, and means cooperating with said belt to effect a corresponding adjustment in the effective diameter of the pulley carried by the other shaft when said first-named pulley is adjusted.
10. 3. In a device of the class described, a first shaft and a second shaft substantially parallel therewith, a resiliently expansible V-pulley on one of said shafts, an expansible V-pulley on the other of said shafts and comprising a coned disc fixed to said other shaft and a mating coned disc held against axial movement, an edge-active belt providing a driving connection between said pulleys, and means for shifting said other shaft axially.
15. 4. In a device of the class described, a shaft, a second shaft substantially parallel with said first-mentioned shaft, an expansible V-pulley mounted on each of said shafts and each comprising an axially fixed coned disc and a mating axially shiftable coned disc, an edge-active belt providing a driving connection between said pulleys, means for shifting one of said shafts axially, and means for causing one of said axially shiftable discs to partake of the axial movement of said shaft and for causing the other of said axially shiftable discs to move correspondingly.
5. In combination, a motor having a spindle, an expansible V-pulley drivingly associated with said spindle and comprising a coned disc fixed to said spindle and a second coned disc cooperatively associated therewith, a shaft substantially parallel with said spindle, a resiliently expansible V-pulley mounted on said shaft, an edge-active belt providing a driving connection between said pulleys, and means for shifting said motor in the direction of the axis of said spindle to move said first-mentioned disc toward and away from said last-mentioned disc.
10. 6. In combination, a motor having a spindle, an expansible V-pulley drivingly associated with said spindle and comprising a coned disc fixed to said spindle and a second coned disc cooperatively associated therewith, means holding said last-mentioned disc against axial movement, a shaft substantially parallel with said spindle, a resiliently expansible V-pulley mounted on said shaft, an edge-active belt providing a driving connection between said pulleys, and means for shifting said motor in the direction of the axis of said spindle.
15. 20. 25. 30.
